UNITED STATES PATENT OFFICE.

JACOB S. PEACOCK, OF LANCASTER, PENNSYLVANIA.

TRACTION-WHEEL.

SPECIFICATION forming part of Letters Patent No. 366,243, dated July 12, 1887.

Application filed December 8, 1886. Serial No. 221,039. (No model.)

To all whom it may concern:

Be it known that I, JACOB S. PEACOCK, a citizen of the United States, residing at the city of Lancaster, county of Lancaster, State 5 of Pennsylvania, have invented a new and useful Improvement in Traction - Wheels, of which the following is a specification.

This improvement is applicable to the wheels of ordinary draft or steam propelled wagons, 10 or to special wheels constructed for the same.

The object of the improvement is to simplify the construction and reduce the cost of the same, and in their use to save wear and expense of haulage, while increasing the tractive power of the animals or steam-drag attached to the wagons provided therewith.

The drawings herewith will give an expert a clear comprehension of my improvements, like letters of reference indicating like parts.

Figure 1 represents in full front elevation a view of my preferable style of wheel; Fig. 2, a plan on the line *a a* of Fig. 1, showing the saddles and shoes in section; Fig. 3, a detached shoe in side elevation; Fig. 4, a plan of the 15 same; Fig. 5, a front and side elevation of the dust-guard and shoe locking plate; Fig. 6, a front, plan, and side elevation of the shoe-saddle; Fig. 7, a full front elevation of an alternative wheel provided with tension spring 20 pockets; Fig. 8, a plan on the line *a a* of Fig. 7, part in section; Fig. 9, a front elevation of a detached shoe with its tension-spring-pocket connection and dust-guard in place; Fig. 10, a plan of the same; Fig. 11, an elevation of 25 the shoe, showing the bifurcated opening for the saddle-pin, the dust-guard ledges, and securing-bolt holes; Fig. 12, a detached front and side elevation of the dust-guard plate, showing the lock for the saddle-pin; Fig. 13, 30 a front elevation, plan, and end view of the saddle.

In the drawings, A represents the wheel- 45 rim; A', the tire; A², the spokes; A³, the hub; B, saddles in number equal to the shoes to be applied to the wheel, having ears B', which pass snugly over the wheel-rim and are provided with pivotal pins B², cast integral therewith or suitably secured thereto. Lugs B³, with bolts B⁴, serve to secure the same in place.

50 Shoes C, of a length adapted to the wheel, have sides C', admitting of free movement of

the wheel between, are recessed at the center C², so as to clear the ears of the saddle B, and are notched or bifurcated at C³, so as to admit of being passed over the periphery of 55 the wheel upon the pins B² of the saddle. A portion, C⁴, projected beyond the recesses C², is provided with undercut or beveled ledges C⁵, within which dust-guards D, provided with keeper-lugs D', are fitted. Said lugs enter 60 within the top of the bifurcation C³ of the shoe, and bolts or rivets being introduced in the holes C⁶ D² after the shoes are in place upon the pins B², the shoes are removably secured thereto.

E represents annular rings adapted to be placed, one at the front and one at the rear of the wheel, over the hub of the same. They may be cast or forged metal, and are removably secured in place by bolts E', said bolts 70 also acting as pivots for the heads F of spring-pockets G, said heads internally threaded at F', to fit threads upon the ends of the barrels or pockets G. A cap, G', at the opposite end, also internally threaded, and bored at G² to 75 suit the spring compressing-rod H, completes the spring case. A rod, H, having a cross-arm, H', bored to suit the pin-connection with the dust-guard, is adapted to slide freely in the bore G² of the cap G', has its inner end 80 provided with a washer, H², of a diameter permitting its free movement in the barrel G, and a wire coiled spring, I, is constructed to occupy the entire space between the washer H² and cap G'. When the head F and cap G' 85 are in their normal positions, the case or pocket G merely gripped at each end, the tension of the spring I is increased or diminished by screwing the barrel into the head F and screwing up the cap G' upon the same, thus 90 decreasing the length of the barrel or pocket and increasing the compression of the spring and its pull upon the rod H and the shoe-plate, to which it is connected by a pivotal bolt, H³. Saddles B, with ears B' and shoe pivotal pins 95 B², are secured upon the inner face of the rim of the wheel by bolts B⁴.

Shoes J, adapted to the wheel, are provided with sides J', and recesses J² at the center of the same, to clear the saddle-ears B'. They are 100 notched or bifurcated at J³, to admit of being slid upon the pins B² of the saddles B, and are

provided with bevel undercut ledges J^4 and bolt or rivet holes J^5 . Fitted to the beveled ledges are dust-guards K , having keeper-ledges K' , adapted to enter the top of the bifurcated notch J^3 , with bolt or rivet holes K^2 , and an extension or arm, K^3 , with pivot-hole K^4 , whereby the cross-arm H' of the rod H is connected with the arm and shoe pivotal bolt H^3 , passing through the same.

- 10 To apply the improved shoe after the saddles B have been secured in place, the shoes are lifted and placed upon the periphery of the wheel, with the pins B^2 of the saddles within the notches C^3 or J^3 of the shoes. The 15 dust-guards D or K are then slid into their places in the undercut slides C^6 J^4 , and are permanently or removably connected with the shoes by using either rivets or bolts in the holes C^6 D^2 or J^6 K^2 , as the case may be. In 20 the first wheel this completes the attachment. In the second wheel a pivotal pin, H^3 , is passed through the extended arm K^3 and cross-arm H' of the spring pocket and completes the connection with the spring-pockets 25 swinging central to the wheel upon the clamping-bolts E' .

Having disclosed my invention, shown its application, detailed its construction and use, I desire to claim as follows:

- 30 1. As an improvement in traction-wheels, a saddle, B , adapted to be applied to the inner face of the rim, having ears B' and pivot-pins B^2 cast or formed integral therewith, said ears clasping the sides of the rim between the same 35 and removably secured to the rim by bolts B^4 , in combination with the slides D and shoes C , as shown, and for the purpose set forth.

2. As an improvement in traction-wheels provided with saddles, as shown and described, 40 shoes C , having side flanges, C' , recessed at

their centers C^2 to clear the saddles B , a raised portion, C^4 , with bifurcated notch C^3 , beveled slides C^6 , and securing-holes C^6 , in combination with the pins B^2 of said saddles, and a dust-guard and locking-plate, substantially as 45 and for the purpose set forth.

3. As an improvement in traction-wheels, the combination therewith of the shoes by saddle pivotal pins B^2 , removably locked thereon by the bifurcated notch C^3 , and keeper-lug D' 50 of the dust-guards, secured in the slides C^6 by bolts or rivets in holes C^6 D^2 , substantially as set forth.

4. As an improvement in traction-wheels, the combination therewith by annular plates 55 E and pivotal clamping-bolts E' , of transverse central spring-pockets having heads F , adapted to pivot or vibrate upon said clamping-bolts, a coiled spring, I , and washer H^2 , sliding free in said pockets, secured to a rod, H , 60 having cross-arm H' , connected with dust-guard locking-plates K by pivotal bolt H^3 , with shoe J by bolts or rivets in holes K^2 J^5 , substantially as and for the purpose described.

5. In combination with the shoes of a traction-wheel, provided with central spring-pockets, as shown and described, the dust guards and locking-plates K , having keeper-lugs K' , adapted to enter the bifurcated notch J^3 of said shoes, an extension-arm, K^3 , connected 70 with the cross-arm H' of the spring-pocket rod H by pivotal bolt H^3 , the sides of the dust-guard plates fitted to slide in the undercut ledges J^4 , and removably secured in place by bolts or rivets in holes J^6 K^2 , substantially 75 as and for the purpose set forth.
